F. W. MAGEE

WATER HEATER

Filed Nov. 25, 1922

FIG. 1

FIG. 2.

FIG. 5.

INVENTOR
FREDERICK W MAGEE

BY *F. W. Magee*

Patented June 5, 1923.

1,457,890

UNITED STATES PATENT OFFICE.

FREDERICK WILLIAM MAGEE, OF LONDON, ONTARIO, CANADA, ASSIGNOR OF ONE-HALF TO THOMAS WILLIAM BAKER, OF LONDON, ONTARIO, CANADA.

WATER HEATER.

Application filed November 25, 1922. Serial No. 603,363.

To all whom it may concern:

Be it known that I, FREDERICK WILLIAM MAGEE, a subject of the King of Great Britain, and a resident of the city of London, in 5 the county of Middlesex, in the Province of Ontario, Canada, have invented certain new and useful Improvements in Water Heaters, of which the following is the specification.

10 My invention relates to improvements in water heaters and the object of the invention is to devise a heater which is simple, cheap and efficient and of a class particularly adapted for use in rural districts or 15 in places where gas or electricity and like sources of power are unavailable and at the same time to devise such a heater as will prevent contamination of the water by smoke, smuts or noxious gases rising from the fire 20 bed and further in which means are provided for preventing the warping of the heater parts liable to take place when subject to the radiation of heat from fuel such as coal, coke and the like and it consists es- 25 sentially of the following arrangement and construction of parts as hereinafter more particularly explained.

Fig. 1 is a side elevation of my heater.

Fig. 2 is a cross sectional view through 30 Fig. 1.

Fig. 3 is a plan sectional view on line 3—3, Fig. 2.

Fig. 4 is a fragmentary detail showing the mechanism for simultaneously operating 35 the smoke damper and hot air damper.

Fig. 5 is a fragmentary detail showing means for journalling the smoke damper within the smoke pipe.

In the drawings like characters of refer- 40 ence indicate corresponding parts in each figure.

1 indicates the body of my water heater of the type disclosed by my United States Patent No. 1,328,682, dated January 20, 1920 45 which consists generally of an outer casing 1^x carrying the condensing apparatus 2 and water distributing apparatus 3, such water distributing apparatus consisting of a dished receptacle 4 through which extend tubular members 5, the condenser 2 being provided with a central orifice 6 from which extends the outlet pipe 7, such outlet pipe extending through the condenser cover 8, of a deflector plate 9 having a central orifice 10 and 50 a lower water distributing device 11 sup-

ported in a dished receptacle 12 having a central orifice 13. The condenser cover 8 is provided with a water supply pipe 14 and the receptacle 12 with a water discharge pipe 15.

60 The outer casing 1^x of the body 1 extends downward below the dished receptacle 12 so as to form a fire pot provided with a lining 16 of fire clay or other suitable material. The upper edge of the fire clay 16 is spaced apart from the lower face of the receptacle 12 and supports a disc 17 around its edge. The disc 17 is provided with a central orifice 18. The dished receptacle 12 is provided around the central orifice 13 with an annular 70 flange 12^x. 19 is a sleeve which extends through the orifice 18 and through the orifice 13 of the receptacle 12, the lower end of the sleeve 19 being provided with an out-turned annular flange 19^x.

75 When the sleeve 19 is slipped upward through the orifices 18 and 13 the upper edge of the sleeve which protrudes above the flange 12^x is turned over the upper edge of such flange as indicated at 19°. 20 is a damper rod which extends through the front of the casing 1^x and through the sleeve 19 and is provided with a damper 21 operating within the sleeve 19 for a purpose which will hereinafter be set forth.

80 The outer end of the damper rod 20 is provided with a T end. 22 is a grate frame resting upon a casing 24 forming the ash pit and 23 is a grate. 25 is an orifice formed in the fire pot provided with a surrounding 90 flange 26. 27 is a smoke pipe damper rod journaled in the flange 26 preferably by forming a notch 28 therein at diametrically opposite points. 29 is a damper secured to the damper rod 27 so as to operate within the flange 26 and open and close the passage through the orifice 25.

95 30 is a pipe extending from the flange 26, such pipe being turned vertically upward to form the smoke pipe of the device and into 100 which the pipe 7 leads. The lower end of the pipe 30 is also preferably notched at diametrically opposite points so as to extend around the smoke damper rod in opposition to the notches 28. 31 is a crank extending from the outer end of the smoke damper rod 27. 32 is a pulley mounted in a bracket 33 carried by the heater. 34 is a double wire as indicated at 35 and 36 extending around the pulley 32 and connected at 105 110

one end to each end of a lever 34^x mounted on a suitably supported bracket 40. The lever 34^x is provided with a forked lower end 34^y engaging a pin 41 extending from 5 the crank arm 31. Each opposite end of the wire 34 is secured to each end of the T portion of the valve rod 20.

By this means it will be seen that when 10 the damper 21 is turned to the horizontal or closed position the damper 29 will be turned to the open position and also when the damper 21 is turned to the open position the damper 29 is turned to the closed position.

It will be seen from this description that 15 after the smoke and gases have passed off from the fuel and such fuel has become incandescent there is a clear passage for heated air upward through the sleeve 19 so directed by the opening of the valve 21 and closing 20 of the valve 29 and through the heater by the orifice 10, tubes 5 and orifice 6 to the outlet 7 leading to the smoke pipe 30.

When it is desired to start the heater and a fresh fire is made or fresh fuel is put on 25 the fire bed the damper 21 is closed and the damper 29 opened simultaneously. The smoke and noxious gases rising from the fire thus pass directly outward through the orifice 25 into the smoke pipe and are carried 30 off. When all the noxious gases have passed off and the fire has ceased to produce smoke or gas the valve 21 is opened and the valve 29 closed. The hot air then passes from the fire pot directly upward through the heater 35 and through the water which is fed thereto to heat it as fully set forth in my prior United States patent hereinbefore referred to.

The disc 17 forms means for preventing 40 the great heat generated by fuel such as coal and coke detrimentally affecting the lower end of the heater body which would otherwise be warped and thereby have its usefulness destroyed.

It will thus be seen that water is heated 45 without being contaminated by smoke or smuts which will dirty clothes when the water is used for laundry work and also prevents it being contaminated with gas 50 which would not only discolour the clothes but render the water unhealthy for washing or bathing in, all smoke, smuts and noxious

gases passing through the outlet 25 directly from the fire pot without passing through the heater, pure heated air only passing up 55 through the heater to heat the water.

It will thus be seen that I have devised a heater which is particularly adapted for using fuel of the smoke emitting type such as coal, coke, wood, charcoal and the like, which 60 fuels not only produce smoke but produce fine sparks during the initial firing of the fuel which fly upward and if permitted to mix with the water produce smuts which 65 will dirty clothes and be detrimental in other ways.

What I claim as my invention is:

1. In a water heater, a chamber having a chimney outlet at its upper end and through which a multiplicity of streams of water is adapted to freely fall, a port at the lower end of the chamber, means for preventing the falling water passing through such port, a source of heat located beneath the chamber and adapted to use smoke emitting fuel, the 70 products of combustion from which pass upward through said port to the aforesaid chimney outlet, means for preventing such products when smoke laden from passing upward, and a separate discharge for such smoke laden products extraneous to the 75 aforesaid chamber.

2. In a water heater, a chamber having a chimney outlet at its upper end, a dished water receiver at its lower end having a port opening therein, means for feeding water to fall in a multiplicity of streams through said chamber, means for preventing the falling water passing through said port, a fire-pot adapted to use smoke emitting fuel 80 located beneath the chamber, a smoke outlet therefrom, and a movable closure for the aforesaid port adapted to prevent the passage of the smoke laden products of combustion passing up through said port into 85 contact with the water and whereby such smoke laden products are directed through the aforesaid smoke outlet from the fire-pot and to permit the products of combustion 90 when free from smoke passing upward into 95 contact with the water falling through the aforesaid chamber.

FREDERICK WILLIAM MAGEE.
